UNITED STATES PATENT OFFICE.

GOTTLIEB STEINER AND JACQUES BOHLI, OF SOLOTHURN, SWITZERLAND, ASSIGNEES
TO THE FIRM SCINTILLA, OF SOLOTHURN, SWITZERLAND.

WIRE-CLAMPING TERMINAL FOR LOW-VOLTAGE INSTALLATIONS.

1,424,219.

Specification of Letters Patent. Patented Aug. 1, 1922.

Application filed July 6, 1921. Serial No. 482,809.

To all whom it may concern:

Be it known that we, GOTTLIEB STEINER, a citizen of the Swiss Republic, residing at No. 304 Obach, Solothurn, Switzerland, and JACQUES BOHLI, a citizen of the Swiss Republic, residing at 304 Obach, Solothurn, Switzerland, have invented certain new and useful Improvements in Wire-Clamping Terminals for Low-Voltage Installations (for which we have filed applications in Switzerland June 24, 1920, and Germany, June 25, 1920), of which the following is a specification.

In low voltage installations for particular purposes, such as for instance for lighting motor cars and the like it is necessary to use electric lead connections that have to be undone very frequently. Such connections have as a rule a form of flexible lead ends which are fixed in position by means of screws that can be slacked back. Repeated fixing frequently results in damaging the core of the flexible leads which consists of a number of thin wires.

A terminal embodying the improvements of the present invention is constructed in such a manner as to exclude any damage to the lead end that is to be clamped. This is effected by providing a screw-threaded hole in the main body of the clamp which is bifurcated on its upper part, and introducing into this hole from above, a screw carrying at its lower end a clamping jaw that is swivelled on a pin.

This clamping jaw is movable up and down in the slot of the clamp body and is adapted to press the end of the lead that is to be clamped, against the lower part of the clamp body.

Further, a cap is slipped from above over the clamp body, this cap leaving the head of the screw free and being bifurcated at its lower part and having its lower edge turned over the clamp body.

Fig. 1 is a longitudinal section of the clamp;

Fig. 2 is a side elevation, and

Fig. 3 is a cross-section thereof taken on the line A A.

The body *a* of the clamp is bifurcated at its upper part into two portions *a*₁ and *a*₂, and is formed with a screw-threaded hole.

A screw *b* working in this screw-thread carries a pin *f* to which is swivelled a block *c*. This block *c* engages by means of wings on both sides into the slots between the portions *a*₁ and *a*₂ of the clamp body.

A cap *d* which is bifurcated at its lower part and is turned over at its lower edge, prevents separation of the elements of the clamp.

The flexible lead end *e* is inserted into the slot provided in the lower part of the cap *d*, and on the screw being tightened the said end *e* is clamped between the lower part of the clamp body *a* and the block *c* which is attached to the pin *f* of the screw and which is suitably formed on its lower face.

What we claim is:—

A wire clamping terminal for low voltage installations including a clamp body bifurcated at its outer end, said outer end being also internally screw-threaded, a screw engaging in said screw-threaded outer end, a pin attached to the inner end of said screw, a clamping jaw, slideable up and down in a slot between the bifurcated parts of said clamp body, and loosely attached in a swivellable manner to said pin and a cap whose outer end is perforated to permit access to the outer head of the screw, said cap being bifurcated at its inner part and having its inner edge turned over the clamp body.

In testimony whereof we have signed our names to this specification.

GOTTLIEB STEINER.
JACQUES BOHLI.
